(57) CLAIM

The ornamental design for a combined garbage and recyclables receptacle, as shown and described.

DESCRIPTION

FIG. 1 is a top view of the combined garbage and recyclables receptacle.

FIG. 2 is a bottom view thereof.

FIG. 3 is a right side view thereof.

FIG. 4 is a left side view thereof.

FIG. 5 is a front view thereof.

FIG. 6 is a rear view thereof.

FIG. 7 is a top left perspective view thereof; and,

FIG. 8 is a top left perspective view thereof, shown in condition of use.

The broken lines shown in the Figures are for the purpose of illustrating portions of the combined garbage and recyclables receptacle that form no part of the claimed design. The liner shown in broken lines in FIG. 8 is to show environment.
